SASH LOCK

Paul L. Geer, Los Angeles, and Harold H. Hall,
Inglewood, Calif.

Application March 18, 1948, Serial No. 15,608

1 Claim. (Cl. 292—206)

1

Our present invention relates to an improved sash lock of the type especially adapted for use with the conventional double hung sash currently used in most buildings and designed to permit a limited opening of one sash but preventing further relative movement of either sash.

The lock of our invention is adapted to be mounted on the inner wall of the frame of the upper sash at a point perhaps six inches above the lower sash and may be adjusted to limit the sash movement or to a position out of the path of the lower sash so that the window may be fully opened.

In the accompanying drawings we have illustrated one complete example of the physical embodiment of our invention according to the best mode we have thus far devised, but it will be understood that various changes and alterations may be made in the exemplified structure within the scope of the appended claim.

In the drawings:

Figure 1 is a fragmentary front elevational view of a pair of sashes showing the lock in position to limit sash movement.

Figure 2 is a vertical transverse sectional view looking toward the lock.

Figure 3 is a horizontal sectional view looking down on the lock.

Figure 4 is a top plan view of the lock.

Figure 5 is a horizontal sectional view of the lock.

Referring now to the accompanying drawings wherein we illustrate the present preferred embodiment of our invention, we employ the side frame 2 of an upper sash having a bottom frame 4, one corner of the frames being routed at 6 and the other grooved to receive the pane of glass 8 secured by putty 10.

The lock of our invention consists of a metal plate 12 having a pair of holes 14 therethrough for screws 16 by means of which the plate is secured to the routed corner of the side frame

2. An angular extension 18 has an opening 20 for screw 22 to secure the plate to the inner face of side frame 2.

One edge of the plate is curled at 24 and cut out to form spaced abutments 26. The arm 28 has an aperture 30 countersunk at 32 and the pin 34 is secured to the plate 12 by cap nut 36 having a flange 38 receivable in the countersunk aperture of the arm 28. A coiled spring 40 is

located about the pin and is confined by nut 42 formed with a cylindrical housing 44. The end of the pin 34 may be burred or deformed to prevent the cap nut from being removed.

With the lock mounted as described it will be apparent that by turning the cap nut counterclockwise, tension on the spring will be lessened and the arm 28 may be raised or lowered as desired, the arm being lifted to pass over the abutments.

With the arm in desired position however, the cap nut is turned home gently to exert sufficient pressure on the arm to prevent its displacement. As extended in Figs. 1, 2 and 3 the arm 28 will be in the path of movement of the lower sash from 46 and will prevent movement thereof beyond the lower edge of the extended arm.

Having thus fully described our invention, what we claim as new and desire to secure by Letters Patent is:

A sash lock for double-hung sash frames comprising a plate adapted to be secured to the upper sash, an extension arranged angularly with respect to said plate, there being an opening in said extension for receiving a securing element, one edge of said plate being provided with a pair of spaced abutments, an exteriorly threaded pin projecting through said plate and spaced from said abutments, an arm pivotally mounted on said pin for movement into and out of position between said abutments, said arm being provided with a countersunk aperture, a cap nut threaded on said pin and having a flange seated in said countersunk aperture, an exteriorly knurled housing threaded on said pin, and a coil spring circumposed on said pin and enclosed by said housing, said spring bearing on said arm, whereby the pressure of said spring holds the arm in between the abutments.
